(57) **CLAIM**

The ornamental design of a center wheel cap as shown and described.

DESCRIPTION

FIG. 1 is a front perspective view of a center wheel cap showing my new design;

FIG. 2 is a rear perspective view thereof;

FIG. 3 is a first side view thereof, the opposite side being a mirror image of the first side view;

FIG. 4 is a second side view thereof, the opposite side being a mirror image of the second side view;

FIG. 5 is a front view thereof;

FIG. 6 is a rear view thereof; and,

FIG. 7 is a front view thereof, shown in its position of use. The broken lines in FIG. 7 are included for the purpose of illustrating an environmental structure and form no part of the claimed design.
